UNITED STATES PATENT OFFICE.

EUGENIO AGNELLI, OF NEW YORK, N. Y.

MECHANICALLY-OPERATED FIGURE TOY.

Application filed May 13, 1926. Serial No. 108,730.

This invention relates generally to coin slot machines used to amuse or interest the public in general, the invention having more particular reference to a novel type of coin slot machine.

An object of the invention is the provision of an improved slot machine in which figures or miniature people, and objects may be moved or operated when a coin is inserted 10 and a handle turned.

The invention has for further object the provision of an improved coin slot machine of novel construction and arrangement of parts.

For further comprehension of the invention, and of the object and advantages thereof, reference will be had to the following description and accompanying drawing, and to the appended claims in which the various novel features of the invention are 20 more particularly set forth.

Fig. 1, of the drawings, is a perspective view of my improved coin slot machine, showing certain parts removed, so as to 25 expose certain interior parts.

Fig. 2, is a vertical side sectional view thereof.

Fig. 3, is a longitudinal sectional view taken on the line 3—3 of Fig. 2.

Fig. 4, is an enlarged sectional detail view 30 of the operating handle and connected parts.

Fig. 5, is a similar view of the counter-shafts, gears and pinions.

As here embodied my improved coin slot 35 machine embodied as container 10, of box-like construction, of any suitable size, and having an inclined or slanting element 11, provided with an eye piece 12, of a suitable shape, having a transparent member 13, 40 glass, celluloid, or the like, suitably attached thereto.

The shaft 14, is attached to the partition 45 16, of the container 10, as at 15, and extends through the container 10, and has slidably mounted thereon, a clutch member 17, provided with radial serrated teeth 18, a pinion 19, and a circumferential groove 20. The operating handle 21, is attached to the tube 22, by the crank 23. The tube 22, 50 is rotatively mounted on the shaft 14, and is held in a fixed lateral position by the collars 24, attached to the tube 22, and located adjacent to either side of the container 10, and is provided with radial serrated teeth 25.

55 The clutch lever 26, is pivotally attached, as at 27, to a suitable support 28, attached to

the partition 29, of the container 10, and is provided with a forked extremity 30, having extended elements 31, adapted to engage the circumferential groove 20 of the clutch member 17. The clutch lever 26, is provided with an extended portion 32, having its extremity 33, located or positioned directly below the lower extremity 34, of the vertical tube 35. The vertical tube 35, extends upward, and through the inclined element 11 of the container 10.

The counter shaft 38, is rotatively mounted in the support 40, and is located or positioned thereon, by the collars 39, located adjacent to the support 40, attached as at 41, by screws, bolts, or the like, to the container 10, so as to rotatively support the shaft 38. The gear 41' and the pinion 42, are attached to the shaft 38. The pinion 42 meshes with the gear 43, rotatively mounted on the shaft 44, and has attached thereto a pinion 44, the gear 43 and the pinion 44 being positioned on the shaft 44, by collars 45 attached to the shaft 44. The pinion 44 meshes with the gear 46, provided with an extended element 47, rotatively mounted on the shaft 48, and positioned thereon, by the collars 49, attached to the shaft 48. The shafts 44 and 48 are supported by a bracket 50, attached as at 51, by bolts, screws, or the like, to the partition 29, of the container 10.

The rod 53, is pivotally attached, at its upper extremity, to the pin 54, depending from the shaft 38, and concentric therewith. 90 The lower extremity of the rod 53, is pivotally attached to the pin 55, depending from the movable member 56, pivoted, at or near its center, as at 57, to the container 10, and located below the support 58, adapted to cover or enclose the lower portion of the container 10. The rods 59, are pivotally attached to the movable member 56, as at 60, and are pivotally attached as at 61, to any desired objects, figures representing people, men, women, or children, at work, dancing or performing any interesting or amusing attitudes. It being understood that the said rods 59 may also be similarly attached to a ratchet 62, engaging with a ratchet wheel attached to a roller 63, so as to move a belt 64, extended over the roller 65, so as to move objects 66, attached thereto, forward and backwards.

The above described construction being 110 such as will permit a coin, when inserted or dropped in the vertical tube 35, to permit

the lever 26 to engage the above mentioned mechanism, so as to allow the handle 21 when turned or rotated to move the above mentioned figures and objects. It being understood that the above mentioned gearing is of suitable proportions to cause the extended element 47 to engage with the lever 26, when the handle 21 has been turned or rotated sixty revolutions, so as to disengage the 10 above mentioned mechanism.

While I have above described the preferred form, construction and arrangement of the various elements employed, it will be understood that the device is, nevertheless, 15 susceptible of considerable modification therein, and I therefore reserve the privilege of resorting to all such changes as may be fairly embodied within the spirit and scope of the invention as claimed.

20 Having thus described my invention, what I claim as new and desire to protect by Letters Patent of the United States is as follows:—

1. In an amusement machine of the class 25 described, a container, a horizontal platform mounted in said container between the upper and bottom ends thereof, a plurality of figures comprising pivotally attached parts mounted on said horizontal platform spaced 30 apart longitudinally and laterally thereof; a platform pivotally mounted below said horizontal platform adapted to be rocked upon a horizontal axis, and a plurality of levers operatively connected at their upper 35 ends with the pivotally attached parts of said figures and pivotally attached at their lower ends to said pivotally mounted platform on opposite sides of said axis for simultaneously imparting various degrees of 40 pivotized movement to the parts of the laterally and longitudinally spaced figures.

2. In a mechanical toy of the class described, a horizontal platform, a plurality of figures rigidly attached at their base to 45 said platform spaced apart laterally and longitudinally thereof and comprising pivotally attached parts, a platform pivotally mounted on a horizontal axis adapted to be rocked relative to the plane of said horizontal platform, and means comprising levers

operatively attached to said figure parts at the upper ends and to said pivoted platform for simultaneously imparting pivotal movement to the parts of said laterally and longitudinally spaced figures when said pivotally mounted platform is rocked. 55

3. In an amusement machine of the class described, a container having an opening in the upper portion thereof adapted to permit observation of the interior of said container, a horizontal partition disposed between the upper and lower walls of said container, a pivotally mounted platform disposed below said horizontal partition adapted to be rocked relative to the plane thereof, figures comprising pivotally attached parts mounted on and spaced apart through the width and length of said horizontal partition and connecting means pivoted to said platform at one end and operatively connected with said figure parts at the other end for simultaneously imparting pivotal movement to the pivotally attached parts of all of said figures when said platform is rocked. 60

4. In an amusement machine of the class described, a container having an opening in the upper portion thereof adapted to permit observation of the interior of said container, a pivotally mounted platform having a horizontal axis of rotation, a stationary horizontal platform disposed above said pivoted platform, a plurality of movable figures comprising pivotally attached parts mounted on said stationary platform, said figures being spaced apart longitudinally of said horizontal platform; a plurality of levers operatively connected at one end to the pivotally attached parts of said figures and at the other end to said pivoted platform, said levers and pivotally mounted platform being adapted to simultaneously impart pivotal movement to the pivotally attached parts of all of said figures, and operating mechanism comprising a hand crank for rocking said pivoted platform relative to the plane of said stationary platform. 65 70 75 80 85 90 95

In testimony whereof I have affixed my signature.

EUGENIO AGNELLI
